CONVEYER APPARATUS

Walter S. Rugg, Pittsburgh, and Alexander Palmros, Rochester, Pa.

Application December 15, 1936, Serial No. 115,958

14 Claims. (Cl. 302—11)

Our invention relates to material-conveying apparatus and particularly to devices for removing earth and foreign matter from ballast.

In our Patent No. 2,028,688, issued January 21, 1936, is disclosed an apparatus for cleaning ballast in place which is very effective and efficient when the foreign matter to be removed is dry. However, if such matter is wet, the efficiency and capacity of the device are reduced by reason of a tendency of this matter to stick and clog in the material-carrying parts. To eliminate this difficulty, settling tanks of known types could not be employed, as they would be altogether too large in themselves, or with a screening device, for a portable outfit such as is necessary in conjunction with ballast-cleaning machinery.

One object of our invention, therefore, is to provide effective and efficient apparatus for the removal of wet dirt, etc., so that the material-conveying apparatus may have the same capacity with respect to such wet material as when the material is dry.

Another object of our invention is to provide a tubular structure for conveying material by fluid pressure with a substantially helically-wound wire or other means therein for scraping the walls, the pitch of said wire being either substantially constant within the tubular structure or gradually varying relatively to the distance from the driven end, such variation, if employed, being preferably directly in accordance with such distance, to provide effective continuous cleaning of the tubular hose or other structure.

Another object of our invention is to provide apparatus of the character just described in which the pitch of the helical wire near its driven end is preferably less than that near its other end.

A further object of our invention is to provide especially efficient helical wall scraping wire means, by reason of its direction of winding extending in the opposite sense from its direction of rotation.

Another object of our invention is to provide a suction structure for cleaning ballast, together with the above-noted helical scraping means having a pivotal connection therewith, the other end of the helical means having a readily detachable connection with a power-driven means.

A further object of our invention is to provide an apparatus of the character just described in which the detachable connection has a handle extending within the helical wire and being

pointed to reduce resistance to the material moving therewith.

Still another object of our invention is to provide in ballast cleaning apparatus or the like a substantially cylindrical combined conveyer casing and settling chamber with a conveyer structure, including a plurality of bent arms, for conveying material through the casing and scraping the sides and ends thereof, together with a second cylindrical casing communicating with an outlet of the first casing and having a rotatable valve member for continuously unloading and discharging material from the first casing.

A further object of our invention is to provide a rotatable unloading valve with a plurality of flexible, readily replaceable arms, thereby providing particularly effective action and inexpensive maintenance.

Other objects of our invention will become evident from the following detailed description taken in conjunction with the accompanying drawings, wherein:

Figure 1 is a view, partially in section but mainly in elevation, of a portion of a ballast cleaning device organized in accordance with our present invention;

Fig. 2 and Fig. 3 are views in end elevation showing the structure of the respective ends of a portion of the apparatus shown in Fig. 1;

Fig. 4 is a longitudinal sectional view of a part of the apparatus shown in Fig. 1;

Fig. 5 is a view in side elevation of the conveyer structure of Fig. 4; and

Fig. 6 is a view, partially in elevation and partially in section, of a modified form of the hose-cleaning device of Fig. 1.

Referring to the drawings the structure herein shown comprises a combined conveyer casing and settling tank 1 having its lower portion 2 functioning primarily as a conveyer casing and being associated with an unloader valve structure 3 at the discharge end of the casing, and having an upper or settling tank portion 4 through which air may be vented to a suitable discharge pipe 5 or the like. A preferably flexible material-conveying tubular structure, such as a hose 6, is provided, with a rotatable, helically-wound wire or other suitable scraper 7 therein, the free end of which is pivotally associated with a suction structure 8 for insertion in ballast or other matter for cleaning purposes, as hereinafter more fully described.

The conveyer casing 2 may comprise substantially cylindrical casing members 11 and 12 which are provided with suitable legs or supporting

members 13 and 14. It will be understood that one or any number other than the two cylindrical casings shown may be employed, if desired, within the purview of our invention, and that, 5 in such case, other structures such as hose 6 and suction structure 8 will be duplicated.

One end of each of the cylindrical casings, namely, the left-hand end, as shown in Fig. 1, is provided with separate or combined end plates or caps 15 and 16 which are secured as by bolts 17 to the end walls of the casing. One purpose of each of these end caps is to assist in maintaining flexible hose 6 in position in conjunction with a suitable yoke member 18 and an internal sleeve 18 23. Each yoke member 18 has upper and lower bifurcated portions 19 for receiving swivel bolts 20 or similar members which are pivoted on the respective end caps 15 and 16 by means of pins 21. By means of this construction, each tubular 20 structure or hose 6 may be suitably mounted in position by being forced over the hollow boss or sleeve 23 which is associated with each end cap 15 or 16 and extends outwardly therefrom, as clearly shown in Fig. 4. In order to lock the parts 25 in position, whereby yoke member 18 suitably supports and maintains in position the corresponding sleeve 23, a plurality of nuts 22 are provided for the ends of swivel bolts 20. In order to more securely fasten the end 24 of the hose 6 on the sleeve 30 23, a wire or similar wrapping 25 may be employed, as shown in Fig. 4, for example. A suitable end plate or cap 15a is bolted on the right-hand end of casing 2.

The lower or conveyer casing 2 may be of relatively thick metal, as shown by the section in Fig. 35 4, while the upper portion 4 may be of thinner or even sheet metal, since it merely acts as a settling tank and conduit for escape of air. Air flowing into the structure from the hose 6 tends to rise upwardly, as indicated by the arrows, and flows around a horizontal baffle 26 into the central vent pipe or passage 5 which is preferably connected to an exhaust fan (not shown).

In each of the conveyer casings 11 and 12, 40 13 there is a central rotatable shaft 28, as shown in Fig. 4, which operates within a ball bearing 29 disposed within a hollow boss 30 at the right-hand end of each casing, as viewed in Fig. 4. To the extreme right-hand end of the shaft 28, a suitable power-driven member 31 may be secured, such as a sprocket, gear, pulley, or other similar device.

A preferably integral hollow boss or sleeve 31 extends within each casing 11 or 12 from the right-hand end and has welded or otherwise suitably secured thereto a long sleeve 32 which extends for the length of over half of the casing and is provided at its free end with roller bearings 33 for the shaft 28. In addition, a rotatable sleeve 34 extends inwardly from the boss 31, having a 60 roller bearing connection 35 on the long internal sleeve 32, and is secured to a sleeve 36, the left-hand end of which is provided with a suitable plug or cap 37 which has a key 42, for example, for fitting into a slot in shaft 28 to be driven thereby. 65 In this way, rotation of the shaft 28 within the sleeve bearing 32 likewise effects rotation of the outer sleeves 36 and 34 for the purpose of driving the conveyer blades 45, as subsequently described.

70 For the purpose of providing a readily detachable connection between shaft 28 and the helical wire 7, a conical connector 39, preferably of a familiar bayonet connection type, to which wire 7 is secured, is fastened to the left-hand end of shaft 28 and has a handle 40 with a pointed end

41 extending to the left within the helical wire 7, the parts 40 and 41 serving as a handle to readily connect or disconnect the member 39 with a partial turn in order to permit removal of the helical wire 7 from the power-driven shaft 28. The purpose of the small diameter and tapered 5 end of the handle structure 40 and 41 is to provide a minimum of resistance against the material which flows through the hose 6 and past this handle structure.

A double helical ribbon conveyer member, constituting continuous blade portions 45a and 45b, best shown in Fig. 5, extends around the handle structure 41, detachable connector 39, rotatable sleeve 36 and rotatable boss 34, being driven from the latter by means of L-shaped arms 46 which have substantially vertical knife or scraper edges 44 where they come in contact with the end walls 15a of the casing 11 or 12. To further support this helical conveyer ribbon, posts 47 are welded or otherwise secured near the outer end and at other spaced intervals, as desired, of rotatable sleeve 36, the outer ends of the posts being suitably welded or otherwise secured to portions of the ribbon members 45a and 45b.

While I have shown two spaced similarly wound conveyer blades 45a and 45b, as a preferable structure, it will be understood that a single flight or helical edgewise blade of this character, with preferably smaller pitch, may be employed, if desired.

The outer diameter of each edge-wise-disposed ribbons 45a and 45b is such as to substantially fill the interior of the corresponding casing 11 or 12, thus efficiently scraping these cylindrical walls, 35 while the knife edges 44 of end-supporting members 46 scrape the end walls, as previously mentioned, at the one side, and the free ends of the helical members 45a and 45b (shown at the left-hand end of casing 2 in Fig. 4) likewise scrape 40 the adjacent wall.

By clockwise rotation of the powder-driven member 31, as viewed from the right-hand end of Fig. 4, the double helical ribbon conveyer structure is rotated to convey the material from the hose 6 toward the right-hand or delivery end of the casing 11 or 12, at which point a second substantially cylindrical casing 47, comprising the outer casing of unloading valve 3, is provided each of the valves communicating with an opening 49 in the cylindrical wall of the casing 11 or 12, as the case may be, and the unloader valve being suitably secured to that casing by means of bolts 48, for example. It will be understood, however, that valve casing openings 49 may be disposed in the right-hand end plates 15a of casings 11 and 12 to feed directly into valve casings 3 at that point, if desired.

A central shaft 50, which may be driven in any suitable manner, is keyed to a hub portion 51 having a plurality of flexible blade members 52, which, by reason of their rotation, carry sections of material from the corresponding casing 11 or 12 and discharge it from a bottom opening 53 either on to the ground or on to a conveyer belt, 65 if so desired. The blades 52 are preferably of a flexible molded rubber composition having enlarged inner ends 52a fitting in correspondingly shaped slots in hub portion 51. By reason of this flexible construction, each normally curved blade 70 52 rapidly straightens out when it reaches bottom opening 53, as shown, thus imparting a particularly effective ejecting movement to the material being unloaded. Moreover, by reason of employing such molded rubber or the like blades 52, 75

when one is worn, it may be quickly replaced by merely removing the end cap 54 of corresponding unloading valve 3, sliding the worn blade longitudinally out of hub 51 and sliding a new blade in, its inner knob 52a serving to properly hold it in position.

The tubular structure or hose 6 may be of any well known type, one end thereof being secured, as previously noted, to the intake end of the corresponding casing 11 or 12, while the other end is secured to an elbow 58 of suction structure 8, being again preferably held in position by means of wire 51 wound around the end of the hose.

The suction structure 8 comprises a suitable digging or burrowing tool 64 which is relatively long and tapered and provided with perforations 65, being preferably triangular in cross-section. This tool may be readily inserted in ballast between the ties, for example, without removing the ballast from its position, and when suction is applied thereto through the hose, material no larger than the size of the perforations 65 is sucked into the tool and carried through the hose 6 into the corresponding conveyer casing 11 or 12 to be disposed of as previously described. The tool 64 may be replaceable, being secured within an elbow 61 having a threaded or other suitable swivel joint 60 to which the elbow 58 is pivotally secured. A boss or lug 62 is provided on the elbow 61 for receiving an impact member 63 for attachment to an air hammer. The general combination of the suction device and air hammer for this purpose is not part of our present invention, being fully set forth and claimed in our above-identified Patent No. 2,028,688.

By means of swivel joint 60, the burrowing tool 64 may be readily turned in any direction desired without it being necessary to change the position of hose 6. The elbow 58 and 61 insure sufficient clearance over a railroad tie, for example, to permit such flexible burrowing action.

The helical means or wire 7 has one end secured within a loop 66 on a rod 67 the outer end of which has a ball bearing or other suitable swivel connection in a lug 59 on the elbow 58 of suction structure 8. The other end of helical wire 7, after passing over the handle 40 and conical connecting member 39, is wound around a cylindrical portion thereof, as indicated by the reference character 69. In this way, the helical wire and the connecting member 39 are unitary in structure and may be removed or replaced very readily, as previously mentioned, by merely making a partial turn on the handle structure 40.

The function of the helical wire 7 is to effectively scrape or clean the inside of the flexible tubular structure 6 whenever the conveyer apparatus is carrying material in order to maintain the full inside diameter of the hose and prevent clogging or filling thereof. Such a function is particularly desirable in the case of wet material, as otherwise the hose would tend to become clogged and the efficiency and capacity of the apparatus would be reduced. Wire 7 exerts no conveying action, as the material is conveyed through hose 6 by fluid pressure, preferably suction, as hereinbefore described.

Another peculiarity about the helical wire 7, which thus does not act as a conveyer but merely as a scraper, is that it is wound left-hand, while the rotation of the wire as a whole is right-hand. This combination was found to be more effective in scraping material from the walls and thus maintaining it in a loose condition to be sucked

through the hose, than if the wire 7 was wound in the same direction as its rotation.

While the pitch of the wire 7 in Fig. 1 is shown as substantially constant within hose 6, the pitch gradually decreases within the conveyer casing 2 as the wire 7 approaches conical connector 39, as shown in Fig. 4, for a purpose hereinafter more fully set forth. If desired, however, the pitch of wire 7 may be varied gradually from the one end to the other, being larger at the free end or suction structure end and smaller at the interior end or the end attached to the detachable connector 39. This variation in pitch within the hose 6, as shown in Fig. 6 by wire 7a, was also found to be effective in cleaning the hose and may be employed in lieu of a constant-pitch wire 7, if desired.

The pitch arrangement of the helical wire 7 and the rotation thereof in the opposite sense to its direction of winding are the results of various experiments which thus provided not only a more efficient scraping tool but also increased the life thereof. By decreasing the pitch of wire 7 within casing 2 as it approaches the detachable connector 39, greater elasticity is imparted thereto to prevent fracture where it is fastened on to the connector. The particular method of such fastening, moreover, provides a desirable cushioning action.

The operation of our apparatus may be described as follows: Upon providing the necessary power to drive the shaft 28 and, therefore, the helical ribbon conveyer blades 45a and 45b and wire scraper 7, and also creating a suction in the vent pipe 5, dirt and other foreign matter of small diameter may be readily removed from ballast in place, for example, by burrowing the tapered head 64 in any desired direction into the ballast, whereby such material is shaken loose by the hammer attachment and then sucked through the perforations 65 into the tool 64, the material thence passing through elbows 61 and 58 into hose 6 and thence into the corresponding casing 11 or 12 with a minimum of resistance being interposed by the handle member 48 thereto, the air carrying the material suddenly expanding as it enters the combined conveyer and settling tank 4, the majority of the dirt or other material then being carried along by the helical ribbon conveyer blades 45a and 45b to the corresponding outlet 49 and thence through the corresponding unloading valve 3, as previously noted. Some of the material flies upwardly with the air, but drops as the latter approaches the top of the settling tank and is likewise carried by the conveyer into the unloading valve. The action of the helical wire 7 very effectively and efficiently scrapes the walls of the hose 6 to maintain the full inside diameter thereof, whereby wet material is carried along to the conveyer tank just as efficiently as dry material, and thus the capacity of the entire machine is maintained at the same high level, regardless of the degree of moisture in the material being removed.

By utilizing the unloader valves 3 located substantially as shown, a very effective continuous removal of the material pushed to the delivery end of the casings 11 and 12 by the helical conveyer ribbons 45a and 45b is procured, so that a very rapid and effective cleaning of ballast in place, for example, is thus provided. It will be understood, however, that our apparatus may also be effectively employed for other purposes than cleaning ballast.

It will be seen that we have thus provided a very effective and efficient device for conveying material, which is prevented from clogging or reducing the capacity of the apparatus and is 5 conveyed to an efficient unloading valve to provide the desired quick and effective cleaning of ballast or the like.

We do not wish to be restricted to the specific structural details or arrangement of parts here- 10 in set forth, as various modifications thereof may be effected without departing from the spirit and scope of our invention. We desire, therefore, that only such limitations shall be imposed thereon as are indicated in the ap- 15 pended claims.

We claim as our invention:

1. A tubular structure for conveying material comprising substantially helically wound flexible self-sustaining means for scraping the walls 20 of said structure, said means having a power- driven end and the pitch of said means varying directly in accordance with the distance from said driven end.

2. A tubular structure for conveying material 25 comprising a substantially helically wound wire for merely scraping the walls of said structure, the pitch of said wire when extending substantially parallel to its axis being different at spaced regions along its length.

3. A flexible tubular structure for conveying 30 material by fluid pressure comprising substantially helically wound flexible means open along the axis of the helix for scraping the walls of said structure, said means having a power-driven end and the pitch of said means when extending substantially parallel to its axis being different near its driven end from that near its other end.

4. A tubular structure for conveying material 40 comprising a single substantially helically wound flexible member open along the axis of the helix for scraping the walls of said structure, said means having a power-driven end and the pitch of said means when extending substantially parallel to its axis being less near its driven end than that near its other end.

5. A flexible tubular structure for conveying 50 material by fluid pressure comprising substantially helically wound flexible means open along the axis of the helix for scraping the walls of said structure, as distinguished from any conveying of the material, and power means for rotating said helically wound means in the opposite sense from its direction of helical winding.

55 6. A tubular structure for conveying material comprising a substantially helically wound wire for scraping the walls of said structure, said wire having a power-driven end and the pitch of said wire varying relatively to the distance from said driven end, said wire being rotated from said driven end in the opposite sense from its direction of helical winding.

7. A tubular structure for conveying material 65 comprising substantially helically wound flexible self-sustaining means for scraping the walls of said structure, said means having a power-driven end and the pitch of said means varying directly in accordance with the distance from said driven end, said means being rotated from said driven end in the opposite sense from its direction of helical winding.

8. A tubular structure for conveying material comprising a single substantially helically wound flexible member open along the axis of the helix for scraping the walls of said structure, said means having a power-driven end and the pitch of said means when extending substantially parallel to its axis being less near its driven end than that near its other end, said means being rotated from said driven end in the opposite sense from its direction of helical winding. 5

9. In combination, a tubular structure for conveying material comprising substantially helically wound means for scraping the walls of said structure, a suction structure at one end of said tubular structure, said helical means having a 10 pivotal connection therewith, and power-driven means at the other end of said helical means having a readily detachable connection therewith. 15

10. In combination, a tubular structure for conveying material comprising substantially helically wound means for scraping the walls of said structure, power-driven means at one end of said helical means, a readily detachable connection between said two means, and a handle 20 for said detachable connection, said handle extending within said helical means and being pointed to reduce resistance to the material moving therepast.

11. In combination, a tubular structure for conveying material comprising substantially helically wound means for scraping the walls of said structure, a casing attached to the delivery end of said tubular structure, a conveyer structure rotatable within said casing, and a readily 25 detachable connection between said helical means and said conveyer structure. 30

12. A substantially cylindrical casing having a loading inlet and a discharge outlet, and a rotatable valve member within said casing for 40 continuously receiving material from said inlet and discharging material through said outlet, said valve member having flexible blades thereby to produce when they unflex an effective ejecting movement. 45

13. In combination, a substantially cylindrical first casing, a conveyer structure having substantially helically wound edgewise-extending arms for conveying material through the casing and scraping the sides thereof, knife members mounted at the delivery end of said shaft to rotate with said arms and scrape the adjacent end wall of said first casing, said first casing having an outlet in its cylindrical wall at the delivery end, a second substantially cylindrical casing 50 communicating with said outlet and disposed at substantially right angles to said first casing to receive the scrapings from said cylindrical and end walls, and a rotatable valve member within said second casing for continuously unloading and 55 discharging material from said first casing. 60

14. An unloading valve comprising a rotatable member having a plurality of slots therein with enlarged inner ends and a plurality of flexible blades in said slots, said blades being readily removable longitudinally and being held in position by enlarged inner ends fitting in said enlarged inner ends of said slots. 65
